COMBINATION BED AND FOOD TRAY FOR PETS

Gustave H. Herbert, Bronxville, N. Y.

Application April 28, 1950, Serial No. 9,532

Term of patent 14 years

(Cl. D12—2)

To all whom it may concern:

Be it known that I, Gustave H. Herbert, a citizen of the United States of America and residing at Bronxville, county of Westchester, State of New York, have invented a new, original, and ornamental Design for a Combination Bed and Food Tray for Pets, of which the following is a specification, reference being made to the accompanying drawing, forming part thereof.

Fig. 1 is a perspective view, as seen from the front, of the combination bed and food tray for pets, showing my new design;

Fig. 2 is a top plan view of the device shown in Fig. 1; and

Fig. 3 is a side elevational view of the device shown in Fig. 2.

I claim:

The ornamental design for a combination bed and food tray for pets, substantially as shown.

GUSTAVE H. HERBERT.
